UNITED STATES PATENT OFFICE.

CHARLES LESLIE TRAVIS, OF MINNEAPOLIS, MINNESOTA.

LAWN-FAN.

SPECIFICATION forming part of Letters Patent No. 537,087, dated April 9, 1895.

Application filed August 16, 1894. Serial No. 520,443. (No model.)

To all whom it may concern:

Be it known that I, CHARLES LESLIE TRAVIS, of the city of Minneapolis, county of Hennepin, State of Minnesota, have invented a certain new and Improved Lawn-Fan, of which the following is a specification.

The object of this invention is to provide a power operated fan that is especially adapted for being set up by the side of a porch or piazza, or before an open window, for the purpose of creating a current of air across the porch or piazza or through the open window, and thereby cooling the temperature of the air and making it more comfortable for the persons seated within the reach of the fan. The fan may, however, be arranged to be used in houses, offices or other places, and in fact almost any position in which it is desired to use a fan of this class.

The invention consists generally in the construction and combinations all as hereinafter described and particularly pointed out in the claims.

In the accompanying drawings, forming part of this specification, Figure 1 is a front elevation of a fan embodying my invention. Fig. 2 is an enlarged vertical section of the lower part of the device, showing one construction of motor. Fig. 3 is a transverse vertical section on the line $x-x$ of Fig. 2. Figs. 4 and 5 are obverse and reverse perspective views of the flights of the motor. Figs. 6 and 7 are sectional views of the shaft arrangement of the motor and fan respectively. Figs. 8 and 9 are respectively front and side views of a modified form of my device.

In the drawings, 2 represents a suitable standard provided with a base or spreading feet 3, said standard being preferably hollow, and usually formed of a suitable length of hollow pipe threaded at each end, as shown in Fig. 2, and provided with the discharge nozzle 5 secured thereto by a suitable coupling 7.

9 represents the casing of the water motor, which is provided with an opening 11 in its bottom and is secured upon the upper end of the pipe 2, the end of said pipe being screwed into the opening 11 in the bottom of said casing. When a rotative adjustment of the motor and fan with respect to the base is desired, the motor is turned down on the threaded end

of the standard and locked in any desired position by a jam nut 6, as shown in Figs. 8 and 9.

The casing 9 is preferably formed in two sections, divided horizontally and secured together by any suitable means, as indicated in Figs. 2 and 3.

Arranged within the casing 9 is a suitable revolving wheel 13 which may be of any suitable construction. As here shown said wheel consists of a central part or roll having secured thereon a series of flights or buckets 15. See Figs. 2 and 3.

Secured upon the casing 9 are the two bearings 17 and 19, arranged outside of the walls of the casing and constructed to support the shaft 21 which extends centrally through said casing. Upon said shaft 21 is the hollow or tubular shaft 23, to which is secured the water wheel 13, said hollow shaft and said wheel rotating together upon said shaft 21. The shaft 23 is provided with an opening 25, and it is also provided at each end with a plug 27 formed of brass or other suitable material. This plug completely fills the end of the shaft or sleeve 23 and is provided with an opening in its center sufficiently large to permit the shaft 21 to extend through it. Oil is supplied to the hollow shaft 23 through the opening 25 so as to completely fill the inside of the shaft, and it keeps the bearing of said shaft in the plugs 27 completely lubricated.

The bearing 17 before referred to is formed by the wall of the casing itself, said casing being thicker at this point and provided with an opening extending through it, and with a set screw 29 by means of which said shaft 21 is held in position. When it is desired to remove the wheel the shaft 21 is withdrawn and the wheel, tubular shaft 23 and the forked arm may be then removed. The upper part of the casing 9 above the shaft 21 is secured in position in any desired manner.

Arranged in the side of the casing 9 is a nozzle 31 arranged, as a screw to permit longitudinal adjustment, by means of which the stream may be directed as required upon the flights. A coupling 33 is provided on the nozzle by means of which suitable hose 35 may be secured thereto. The nozzle 31 is preferably arranged so as to direct the water passing through it directly toward the center

of the opening 11 in the bottom of the casing, whereby the stream of water from said nozzle strikes each bucket or float on the wheel firmly and moves it sufficiently to bring the next bucket under the end of the stream. In this way the stream strikes firmly upon each bucket or float and impinges upon one before it ceases to act upon the one preceding.

By means of the coupling 33 a suitable hose 10 35 may be connected to the casing for the purpose of leading the water thereto. A suitable hose may also be connected to the outlet end or coupling 5 for the purpose of directing the waste water to any convenient point.

15 This will preferably, in practice, be directed onto the lawn, and the water which runs the motor and operates the fan will at the same time be used for watering the lawn.

Mounted upon the shaft 21 outside of the 20 bearings 17 and 19 is the fork 37, which is arranged to swing freely upon said shaft 21 as a center. To the upper end of the fork 37 is connected the tubular standard or arm 39, to the other end of which is connected a fork 41 25 carrying the shaft 43, and upon this shaft is mounted a tubular shaft 45 having secured thereon the fan wheel 47. The shaft 45 is provided with the, preferably brass, plugs 49 at its end, and with an oil hole 51, by means 30 of which oil may be supplied to the interior of the shaft, while the plugs 49 form bearings upon the shaft 43 for the tubular shaft and fan to rotate upon. The tubular shaft 23 is provided outside of the casing 9 with a suitable 35 wheel or pulley 53, and the shaft 45 is also preferably provided with a similar though smaller pulley 55. A belt 57 extends around these pulleys 53 and 55 so that when the motor wheel is driven by the passage of water 40 through the casing, the wheel 53 will be rotated, and through the medium of the belt the pulley 55 will drive the fan wheel 47 at a high rate of speed.

One arm of the yoke 37 is provided with the 45 quadrant shaped plate 57 which is concentric with the casing 9. The edge of said plate passes between the end of the stationary lug 59 and the inner surface of the threaded thumb-nut 61. The nut 61 is arranged to 50 screw upon a stud projecting from the end of the lug 59 and through the interior of the quadrant shaped plate 57 but close to the edge thereof, so that by turning up the nut 61 at any time the plate 57 may be clamped between the inner surface of the nut 61 and the 55 outer surface of the lug 59. As the plate 57 is connected to and moves with the yoke 37, said plate will always be moved as the fan is swung from one position to another, and by 60 tightening the nut 61 said plate may be fastened and thereby fasten the said fan support in any desired position.

In some instances I prefer to provide modified means for adjusting the fan, adapted especially for adjusting it in a vertical position where such adjustment is desired. In this instance (see Figs. 8 and 9) a vertical rod 63

is secured to the water motor and extends to any desired height. The shaft 43 which supports the tubular shaft upon which the fan is 70 mounted is in the form of a stud pin secured to a sliding bearing 67 supported upon the rod 63 by means of the collars 69. A set screw 71 is arranged upon one of said collars and provides means for securing said bearing at 75 any desired height. This bearing and the rod upon which it is located form a substantial support for the shaft of the fan. The belt wheel or pulley 55 is mounted upon the tubular fan shaft, preferably near the sliding bearing 80 67.

An arm or connecting rod 75 is connected to the shaft or stud pin 43 so as to turn freely thereon. The lower end of said arm is pivotally connected to the upper end of an arm 85 77 by a stud pin 74. A double pulley 83 is mounted on the stud pin 74. The lower end of the arm 77 is provided with a fork 79 which is mounted on the shaft 21 of the water motor. One belt runs from the wheel upon the 90 water motor shaft to one of the grooves in the wheel 83, and the other belt extends around the wheel 83 in its other groove and extends around the wheel upon the fan shaft, so that said fan is driven in substantially the 95 same way as before described by the rotation of the shaft of the water motor.

With this construction the fan may be vertically adjusted to any desired height within the limits of the rod 63, and the driving belts 100 are always kept taut and in position for running the fan.

I do not wish to limit myself to the construction of the water motor herein shown and described, as I may use any suitable motor for operating the driving shaft from which power is transmitted to the fan shaft. By standing the fan by the end of a porch or piazza it is found that a current of air is created that will extend the full length of an 110 ordinary piazza, or by standing the fan outside of an open window upon a hot day air may be circulated throughout the entire house, and the only power required to operate the device is obtained by means of an ordinary 115 lawn hose, and the water after being used for driving the water motor and fan may be conveyed back upon the lawn for the purpose of keeping it thoroughly watered. It will be seen therefore that the device is exceedingly 120 simple in construction, easy of operation and that it is adapted for general use wherever a small power or a pressure of water may be obtained.

Having thus described my invention, I 125 claim as new and desire to secure by Letters Patent—

1. The combination, with the hollow standard, mounted upon a suitable base, of the water motor casing secured upon the upper end of 130 said standard and communicating therewith, the wheel arranged in said casing, the inlet nozzle for directing a stream of water against said wheel and thereby rotating the same,

the swinging arm pivotally supported upon the axis of said wheel, a fan mounted upon said swinging arm, and driving means extending from the shaft of said water motor to said fan shaft, for the purpose specified.

2. The combination, with the hollow standard supported upon a suitable base, the water motor casing arranged upon the upper end of said standard, whereby said standard forms a waste-pipe for conducting the water out of said casing a wheel mounted in said casing, a nozzle for directing a stream of water against the floats of said wheel, a belt pulley upon the shaft of said wheel outside of said casing, a swinging arm mounted upon the axis of said wheel, a fan mounted in bearings upon the upper end of said arm, a driving belt for driving said fan from said water motor, and means for locking said swinging arm in any desired position, substantially as described.

3. The combination, with the hollow standard 2, and the base 3, of the water motor casing secured upon the upper end of said casing 2, the wheel arranged in said casing and provided with a tubular shaft, the shaft 21 mounted in bearings upon said casing and supporting said tubular shaft, the belt pulley 53 secured upon said tubular shaft, the fork 37 supported upon said shaft 21 and provided with the plate 57, the locking nut 61 for locking said plate, the arm 39 secured to said fork and carrying at its upper end the fork 41, the

fan shaft mounted in bearings in said fork 41, the fan arranged upon said shaft, the belt pulley upon said fan shaft, and the belt extending from the pulley upon the motor shaft to the pulley upon said fan shaft, for the purpose specified.

4. The combination, in a lawn fan of the water motor casing, the water wheel and its shaft provided therein, a swinging fan carrying arm pivoted upon said casing or frame, means for driving the fan from said wheel, a standard for said casing and means for supplying and conducting away the necessary water, substantially as described.

5. The combination, with a casing made up of upper and lower halves, of a nozzle carried by said lower part, shaft supports also provided on said lower part, the shaft, the water wheel provided thereon, the concentrically pivoted swinging arm, the fan carried on the upper end thereof, a belt for driving said fan from the rotation of said wheel, a standard whereon said casing is fixed, and an opening in the casing through which waste water may flow, substantially as described.

In testimony whereof I have hereunto set my hand this 11th day of August, A. D. 1894.

CHARLES LESLIE TRAVIS.

In presence of—

C. G. HAWLEY,
A. C. PAUL.
